UNITED STATES PATENT OFFICE.

ESSINGTON N. GILFILLAN, OF CHICAGO, ILLINOIS.

DESIGN FOR A THREAD CASE OR CABINET.

SPECIFICATION forming part of Design No. 27,405, dated July 20, 1897.

Application filed June 10, 1897. Serial No. 640,255. Term of patent 7 years.

To all whom it may concern:

Be it known that I, ESSINGTON N. GILFILLAN, a citizen of the United States, residing at Chicago, in the county of Cook and State 5 of Illinois, have invented and produced a new and original Design or useful Shape for Thread Cases or Cabinets, of which the following, in connection with the accompanying drawings, is a full, clear, and exact specification.

In the said drawings, Figure 1 is a perspective view of a spool case or cabinet embodying my design, looking from the front; and Fig. 2 is a rear elevation thereof.

15 The leading features of my design consist of a spool-case, oblong in plan view, with rounded ends and each end having a semi-cylindrical open front extending partially throughout its height.

20 The general formation of the cabinet is oblong in plan view with rounded ends, like the two halves of a cylinder, each secured to the end of an oblong body. Each of these semi-cylindrical ends is provided with an opening

25 A in its front, extending partially throughout the height thereof and displaying a number of vertically - arranged partitions B. Just below this opening A in each end is an oblong opening C, in each of which are set two curved

doors or slides D. Just below the level of the 30 opening C extends a horizontal bead E, which continues around the cabinet or case over a plain panel or surface F, which also surrounds the cabinet and in one side of which is set a drawer G, having knob g, the base of the 35 cabinet being constituted by an ornamental bead H. In one side of the cabinet above the drawer G is located a rectangular panel I, surrounded by an ornamental bead i, while the opposite side is provided with a similar 40 panel I', surrounded by a similar bead i'. The whole is surmounted by a top piece J, having its under edge beaded and inclining toward the body of the cabinet. At each end of the top is located a knob K, and at a short distance 45 from each of these is a pear-shaped piece L, resting upon the top.

Having thus described my invention, what I claim as new therein, and desire to secure by Letters Patent, is—

50 The new and original design or useful shape for a spool case or cabinet substantially as herein shown and described.

ESSINGTON N. GILFILLAN.
